Primary Examiner — Michelle E. Wilson*Assistant Examiner* — Sanjeev Paul(74) *Attorney, Agent, or Firm* — Wolf, Greenfield & Sacks, P.C.(57) **CLAIM**

The ornamental design for an eyewear temple bar, as shown and described.

DESCRIPTION

FIG. 1 is a top, front, right side perspective view of an eyewear temple bar showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom, front, left side perspective view thereof.

The broken lines represent portions of the eyewear temple bar that form no part of the claimed design.
